2 - n - ALKYL MERCAPTO - BENZOTHIAZOLE DERIVATIVES AND PROCESS FOR PREPARING THE SAME

Albert Sander, Essen, Germany, assignor to Th. Goldschmidt, A. G., Essen, Germany, a German body corporate

No Drawing. Application September 13, 1949, Serial No. 115,568. In Germany October 1, 1948

5 Claims. (Cl. 260—306)

1

It has been found that compounds having valuable capillary-active properties which are excellently suitable for use as detergents, emulsifiers, dispersing agents, foaming agents and wetting agents, and can be employed to particular advantage for economic pickling, are obtained if 2-mercaptop-arylene-thiazole sulphonic acids or 2-mercaptop-arylene-thiazole carboxylic acids in neutral or weakly alkaline solution, if necessary with an addition of suitable solvents, are condensed with aliphatic, hydroaromatic or mixed aliphatic and aromatic halogen compounds, the hydrocarbon chain of which contains at least 5 C-atoms. Preferably, organic halogen compounds may be employed for the condensation, which have branched hydrocarbon chains whose main valence chain consists of at least 5 C-atoms.

It has long been known from technical literature that aliphatic hydrocarbons are given surface-active properties by introducing hydrophilic or solubilising groups either directly or via suitable bridge linkages. Detergents or other auxiliary agents which can be used in practice, however, are in such cases only obtained from those aliphatic compounds whose hydrocarbon chain consists of at least 12 C-atoms. This is so, for example, in the case of the classic detergents, i. e. the soaps, or in the case of the modern purely synthetic washing agents, such for example of the lauryl sulphonates, the mersolates (alkane sulphonate detergents prepared by sulphochlorination of paraffin hydrocarbons), the ultravons (alkyl-benzimidazolesulphonic acids), igepons (alkane sulphonic acids with amide or ester linkages between the hydrophobic and sulphonic groups) and others, which all contain from 12 to 18 or more C-atoms in their hydrophobic part. If aromatic sulphonic acids are joined to aliphatic residues through any intermediate links, the compounds obtained quite generally exhibit unsatisfactory resistance to lime and in addition usually have deficient water solubility, so that washing agents which are of practical use can only be obtained by introducing a number of sulpho or other solubilising groups.

In contrast thereto, it has surprisingly been found in accordance with the present invention that precisely the introduction of shorter aliphatic chains which, according to previous experience, give no useful detergents at all, into the starting substances mentioned at the outset gives compounds having excellent detergent properties, which at the same time have excellent resistance to lime, solubility, foaming power, wetting and cleansing capacity and emulsifying properties,

2

and are excellently suited for use for economic pickling. Contrary to all expectations, it has been found that the optimum effects and properties are obtained with straight or branched aliphatic hydrocarbon chains, the main valence chain of which contains only 6 to 8 C-atoms.

The subsequent introduction of the sulpho group, for example by treatment with suitable sulphonation agents, in which the sulpho group also enters the aromatic nucleus, gives the same result, so that the process according to the invention can also be carried out by first condensing alkali salts of the 2-mercaptop-arylene thiazoles instead of the 2-mercaptop-arylene thiazole sulphonic acids, and subsequently sulphonating the condensation products obtained.

The surprising discovery has also been made that these favourable general properties of the compounds obtainable in accordance with the invention are substantially due to the mercapto group of the benzothiazole molecule, since if the sulphur bridge is replaced by other atoms or atom groups, for example by nitrogen or by the sulphone residue, the properties of the condensation products change in an unfavourable manner, and in particular the water solubility thereof decreases sharply, so that they are practically useless as washing agents.

The process provided by the present invention, the effects of which could by no means be foreseen from the existing knowledge, consequently constitutes a technically and economically very valuable advance, since it is thereby possible to convert lower aliphatic compounds which hitherto could not, or could only to a limited extent, be put to any practical use as by-products of the synthesis of benzine or fatty acids, into valuable articles of use.

Example I

150 parts by weight of disodium-2-mercaptop-benzothiazole-6-sulphonate are dissolved in a closed vessel provided with means for agitation in 600-800 parts of 70%-80% aqueous alcohol, and gradually mixed with 80 parts by weight of 1-chloro-octane with mild boiling. Condensation is then carried out with mild boiling and with reflux cooling for 15-20 hours until the conversion is complete. After the alcohol and the excess chloro-octane have been driven off, which may be done by the usual method, 200-220 parts by weight of the sodium salt of 2-n-octylmercapto-benzothiazole-6-sulphonic acid with a 13%-15% sodium chloride content, are obtained 55 on evaporation of the residual solution in an

3

almost theoretical yield, as a white powder readily soluble in warm water and having an excellent washing, wetting and foaming action.

If, in this example, the 1-chloro-octane is replaced by 2-chloro-octane or mixtures of isomeric monochloro-octanes, more readily soluble products having similar excellent general properties are obtained. Halogenated hydrocarbons having a branched chain, for example 2-ethyl-1-chloro-hexane, also give readily soluble products having excellent washing, wetting and foaming action. The products obtained are remarkable for their excellent resistance to the water-hardening agents and to acids and retain their surface-active properties both in the alkaline and in the acid zone. Due to the fact that they also have excellent stability in strongly acid solution, they are excellently suitable as auxiliary carbonising agents.

Example II

150 parts by weight of the disodium salt of 2-mercaptopbenzothiazole-5-sulphonic acid are condensed with 80 parts by weight of 1-chloro-octane as described in Example I. The sodium salt of 2-n-octyl-mercaptopbenzothiazole-5-sulphonic acid which is obtained in very good yield is entirely similar to the isomeric 6-sulphonate in its properties except that it is of slightly lower solubility. The dodecyl derivative, which can be produced in a similar manner with the aid of dodecyl chloride, also has very good washing properties.

Example III

If, in Example II, the 2-mercaptopbenzothiazole-5-sulphonate is replaced by 130 parts by weight of the disodium salts of 2-mercaptopbenzothiazole-5-carboxylic acid, a readily soluble end product similar to soft soap and having remarkably favourable detergent properties is obtained in very good yield.

Example IV

140 parts by weight of the acid zinc salt of 2-mercaptopbenzo-thiazole-6-sulphonic acid are suspended in 600-800 parts of alcohol with 200-300 parts of water and mixed with such a quantity of 45% soda lye that the zinc is redissolved as zincate. Condensation is then carried out in the manner described in Example I with 80 parts by weight of 2-chloro-octane, and after the reaction is complete the alcohol is distilled, whereafter the residue of the chloro-octane is driven off by steam distillation. The distillation residue, from which the difficultly soluble zinc salt of the 2-octyl-mercaptopbenzothiazole-6-sulphonic acid has precipitated as a white soap-like mass, is brought into solution by acidulation with dilute hydrochloric acid. The zinc is precipitated in the boiling condition with hot soda solution as basic zinc carbonate, and after filtering, the hot filtrate is mixed with an equal volume of saturated sodium chloride solution. The sodium salt of 2-(2-octyl)-mercaptopbenzothiazole-6-sulphonic acid is thus separated in the form of white soap-like crystal scales, which are filtered off after cooling. The odourless product is readily soluble in water, has high foaming and wetting capacity and excellent cleansing power. Highly dilute solutions thereof and those of the isomers render metal surfaces remarkably passive to acids and are therefore excellently suited for use as additions to economic pickling agents.

When, for example, a bright sheet-iron strip of 140 g. in weight was subjected to the action of

4

hot dilute sulphuric acid having a H_2SO_4 content of 7.5% at 80° C., the reduction in weight after a period of action of 4½ hours amounted to 7.1575 g. but when 0.05% of the sodium salt of 2-octyl-mercaptopbenzothiazole-6-sulphonic acid was added to the same acid, only 0.0480 g. of metal was dissolved under the same conditions. The ratio of the increase in passivity is therefore 1:149.

10 Highly rusted sheet-iron specimens were treated for 40 minutes with 500 cc. of 5% hydrochloric acid at 80° C. When no passivity-increasing agents were added, the brisk evolution of gas continued with considerable corrosion even after the layer of rust had been removed. On the other hand, when in a parallel experiment about 0.1% of the capillary-active compounds produced in accordance with the examples of the invention was added, the evolution of gas ceased immediately after the layer of rust had been removed and there remained a bright metal surface without any visible traces of corrosion. The reduction in the weight of the specimen amounted in this case only to one-half of that of the sheet metal treated without the passivity-increasing agent (1.0962 g. as compared with 2.0953 g.) and was thus practically equal to the quantity of rust dissolved.

20 Rusted-in screws can readily be loosened within a short time if treated with a few drops of dilute hydrochloric acid containing about 0.1-0.5% of the products of condensation described in the foregoing examples.

Example V

35 100 parts of weight of 2-octylmercaptopbenzothiazole produced in the known manner by condensation of the sodium salt of 2-mercaptopbenzothiazole in alcoholic solution with chloro-octane, are introduced into 300 parts of 25% oleum with cooling, and sulphonated, if necessary with heating to about 110° C., until a water-soluble specimen is obtained. The sulphonation mixture is then poured into 2000 parts of water and limed out with milk of lime in the hot state and the heavy alkaline solution is separated from the precipitated gypsum by filtration. After the conversion of the filtrate with a soda solution and separation of the calcium carbonate thus precipitated, the product is evaporated to dryness and the sodium salt of 2-octylmercaptopbenzothiazole sulphonic acid, having similar properties to the product obtained in accordance with Example I, is obtained.

Example VI

45 30 parts by weight of disodium-2-mercaptopbenzothiazole-6-sulphonate are condensed in the manner described in Example I with 20 parts by weight of pinene hydrochloride. On working up 50 of the reaction mixture the sodium salt of 2-bornyl-mercaptopbenzothiazole-6-sulphonic acid is obtained in good yield in the form of a white, very readily water-soluble powder. As a derivative of a methylated cyclohexane, it corresponds 55 in its colloid-chemical behaviour to the corresponding limit hydrocarbon derivatives. A notable feature in this case, however, is the extremely great increase in water solubility.

I claim:

70 1. A capillary active substance of the general formula

wherein R is a benzothiazole nucleus, y is a solubilizing group selected from the group consist-

ing of $-\text{COO}$ cation and $-\text{SO}_3$ cation radicals, said radical being attached to the benzene ring of the benzothiazole nucleus, and x is a hydrophobic radical selected from the group consisting of alkyl radicals containing at least 5 carbon atoms and the bornyl radical, said radical $-\text{S}-x$ being attached to the 2 position of the benzothiazole nucleus.

2. A capillary active substance in accordance with claim 1, in which the hydrophobic radical x is an alkyl radical containing 6 to 8 carbon atoms.

3. A capillary active substance in accordance with claim 1, in which the hydrophobic radical x is a branch chain alkyl radical, the main valence chain of which contains at least 5 carbon atoms. 15

4. A capillary active substance of the formula

wherein X is an alkyl radical containing 6 to 8 carbon atoms.

5. A process for the preparation of a capillary active substance which comprises condensing a compound selected from the group consisting of 2-mercapto arylene thiazole carboxylic acids and 2-mercapto arylene thiazole sulfonic acids in a neutral to weakly alkaline solution with a halogenated compound selected from the group consisting of alkyl halides containing at least 5 carbon atoms and pinene hydrohalides.

ALBERT SANDER.
